UNITED STATES PATENT OFFICE.

JOHN J. FRED BRAND, OF ROSEVILLE, OHIO, ASSIGNOR TO HYDRAULIC-PRESS BRICK COMPANY, OF ROSEVILLE, OHIO.

EMBOSSING MACHINE FOR BRICKS.

Application filed August 30, 1927. Serial No. 216,447.

This invention relates to improvements in embossing machines, particularly adapted for embossing brick, clay building materials and the like.

5 An object of this invention is to provide an embossing apparatus which may be easily and inexpensively adjusted to the ordinary brick extrusion machine. The apparatus may be conveniently mounted on the front 10 plate of the extrusion machine which may or may not be a part of the die through which the brick material is extruded.

A further object of this invention is to provide an embossing apparatus which may 15 be readily attached to an extrusion machine of the common type and operated from any suitable source. For instance, it may be operated from a prime mover in such a manner that the speed of the embossing apparatus becomes dependent upon the speed of 20 the moving clay column as it passes through the extrusion machine.

Another object of this invention is to provide means in the embossing apparatus 25 whereby a change of embossing design may be made when desired by simply altering the stroke of the actuating means and the embossing elements, thereby providing a device which, if desired, may operate immediately under the surfaces of the brick 30 material.

Other objects of this invention will appear from the following detailed description 35 of the device and as disclosed in the two sheets of drawings herewith made a part of this application.

In the drawings—

Figure 1 illustrates an elevational view 40 of the embossing machine or apparatus, disclosing its different members in assembled and operative relationship.

Figure 2 represents a sectional view of 45 Figure 1, taken along line 2—2, disclosing a plate suitably attached to an extrusion machine and the embossing device connected with the plate.

Figure 3 illustrates a sectional view of 50 Figure 1, taken along line 3—3.

Fig. 4 illustrates a sectional view of Figure 1 taken along line 4—4.

Figure 5 illustrates a sectional view of the 55 adjusting member for holding and placing the embossing element under tension.

Figure 6 illustrates a perspective view of 60 a brick, disclosing a form of embossed de-

sign thereon, produced by the apparatus described and claimed herewith.

In the embodiment of the invention here-with described, and claimed, numeral 1 designates the front or producing end of an 60 extrusion machine of ordinary make, or other suitable device, to which this invention could be practically applied. The moving clay column from which the brick is manufactured is adapted to be forced under 65 pressure through a die plate 2 and opening 3 therein. The plate 2 may be fastened by any suitable means such as machine screws 4 to the front end of the extrusion machine 1, passing through suitably formed flange 70 portions 5 integrally or otherwise connected to the extrusion machine element 1.

The apparatus for embossing the brick formed by the extrusion machine may be mounted, as disclosed in Figures 1 and 2, 75 upon the die plate 2, however, the particular position of mounting the embossing apparatus upon the machine has no essential bearing upon the merits of the case inasmuch as the device may be suitably connected with 80 the extrusion machine in any other manner provided it would function properly. For instance, the plate holding the embossing apparatus in operative relationship does not have to be the die plate, although this is 85

the form of attachment disclosed in Figures 1 and 2 wherein the device is mounted on the plate 2 in front of the machine element 1 in such a manner that the four rocker arms 6, 7, 8 and 9 are pivotally arranged upon the plate 2 as at 10, 11, 12 and 13, the rocker arms being suitably spaced from the plate 2 by means of washer elements 14 in order to allow for the freedom of movement of the rocker arms. It is preferred in this 90 invention to form the rocker arms in such a manner that they may be operated from a common source of power. In order to accomplish this result, rocker arm extensions 7, 15 and 16 are pivoted at 11; 8, 17 and 18 at 12; 6, 19 and 20 at 10; and 9, 21 and 22 at 13, while pivoted to the rocker arm elements 16, 18, 19 and 21 are link portions 23 and 24, and pivotally connected to the rocker arm portions 20 and 22 is a connecting rod link element 25. A crank element 28 is pivotally or adjustably connected to rocker arms 22, and, as at 26, to an actuated crank element 27, which may be operated by any available source of power; for 100 105 110

instance, the crank element 27 could be operated from a source, the speed of which is dependent upon the speed of the moving clay column as it passes through the die 3. The length of the stroke given to the rocker arms may be varied or regulated by merely changing the crank pin element 28 to connect with the various positions of the pins 29, 30 and 31, it being understood that an unlimited number of strokes or pins may be used without affecting the merits of the invention. At the free ends of the rocker arm elements 6, 7, 8, 9, 15 and 17 are located segmental portions integrally or otherwise connected with the rocker arms 32, 33, 34 and 35, adapted to be suitably grooved for receiving the embossing members 36, 37 and 38 which may be made of any suitable material such as a single plain wire, or two or more wires twisted, or may be made of various shapes such as flats, squares, triangular, hexagonal, straight or twisted. If desired, any of these types could be fitted with various shaped bars, lugs or the like depending on the nature of the embossing surface sought. Obviously, the embossing elements may be made of any material adapted to be held in operative relationship in the rocker arms for the purpose of embossing the building material, such as brick.

In order to securely hold the embossing members 36, 37 and 38 in operative relationship, one end of each embossing member is adapted to be securely held as at 39 and 40 in the segmental portions 41 and 42, and as at 43 in the segmental portion 33. The free ends of the embossing elements 36, 37 and 38 are extended loosely over the co-operating segmental portions 32, 34 and 35 and brought under adjustable tension by means of holding elements 44, 45 and 46 which are adapted to be threaded at one end and extended through the arm portions 16, 20 and 22 in such a manner that the embossing members may be brought under adjustable tension over the segmental portions by means of adjusting nuts 47.

In order to provide for the proper guiding and adjustment of the embossing elements 36, 37 and 38, lug portions 48 are adapted to extend over the plate 2 for receiving adjusting screws 49 which are adapted to cooperate with a member 50 slidably positioned upon the plate 2. A guiding roll 51 is rotatably mounted in the sliding member 50 by means of a bolt element 52 or any other suitable device, the guiding roll 51 to be so positioned within the sliding element 50 that the embossing members may be guided either on the inner or outer side thereof. A plurality of adjusting and guiding devices, as disclosed in Figure 4, are preferably positioned for the purposes of this invention as disclosed in Figure 1 on the plate element 2, although it is to be understood

that the number and arrangement of the guiding and adjusting elements has no effect upon the merits of the invention, that is, a sufficient number of the adjusting elements should be used in order to obtain efficient adjustment, when desired, of the embossing portions 36, 37 and 38 for producing a brick as disclosed in Figure 6, having an embossed design 53 thereon.

In operation, this invention provides an apparatus for embossing brick, clay building materials and the like. The device in general is mounted on a plate which may or may not be a part of the die of an extrusion machine. The drawings disclose it mounted on the front of the machine as clearly shown in dotted lines at 54 in Figure 1. The device as described and claimed herewith is extremely simple, efficient and inexpensive, comprising, primarily, four rocker arms or quadrants pivotally mounted on the plate. These quadrants are connected and actuated by a rod driven from a crank element or any other suitable device. The crank may be operated from any proper type of motor, although it is preferred to operate it from some source having a speed which is dependent upon the speed of the extrusion machine and the moving clay column being extruded therefrom. The length of the stroke of the embossing members which are connected with the rocker arm quadrants can easily be regulated by changing the stroke of the crank pin or by some other suitable means such as the use of various shaped cams in connection with springs whereby it would be possible to operate an almost unlimited change in the pattern of the embossing. By utilizing the means just described, the pattern may be varied materially from the ordinary zigzag lines on the face of the bar of clay. For instance, at least four changes may be obtained, such as a vertical line when the twisted wires are at rest, a short diagonal line when a short movement of the wire occurs, and a long diagonal line when the movement is longer, while a curved line would result from a varying speed. These curved lines could be made short, long or medium, the same as the others. The pitch of the diagonal and curved line would, of course, be varied by the speed of the clay column and the movement of the wire embossing elements.

In the invention herewith described, the embossing members may operate on the surface or immediately below the surface of the bar of clay, as desired. In the latter case, the peeling, if allowed to crinkle as in oak bark designs, might be rolled down with the curly effect shown in the background between the crinkled peels, or, if desired, the peeling may be removed entirely, exposing the full embossed surface. These

embossing members may be made as above described in any suitable materials, and are attached to the faces of the rocker arms or quadrants in such a manner that any desired tension may be secured. The segmental portions are grooved in order to properly guide and hold the embossing members in operative relationship. Proper lateral adjustments may be easily made by means 10 of the adjusting and guiding elements located where needed for efficient operation on the plate of the apparatus.

The embossing device, according to this invention, does not necessarily have to be 15 mounted on an extrusion machine, but anywhere it would have proper contact with the severed as well as the unsevered portions of the clay column. When attached to the extrusion machine, it is the unsevered column 20 instead of the severed column (brick) which is embossed. The embossed column is then severed into blocks, bricks or other building units. It is to be understood, however, that in this invention, the column of 25 clay may be embossed either before or after severing; that is, before cut into bricks, or it may be cut into bricks and each brick embossed afterwards.

What I claim is:

30 1. In an embossing machine for a bar of clay, a plurality of rocker arms, an actuating element for moving each arm simultaneously, embossing members attached to the rocker arms in such a manner that on a 35 movement of the arms the embossing member will contact with the bar of clay in a predetermined manner, means for varying the nature and stroke of the embossing member consisting of portions arranged on the 40 actuating element, suitable means attached to the machine for adjusting and guiding the embossing.

45 2. In an embossing machine for a bar of clay, a plurality of rocker arms, an actuating element for moving each arm simultaneously, embossing members attached to the rocker arms in such a manner that on a movement of the arms the embossing member will contact with the bar of clay in a predetermined manner, means for varying the 50 nature and stroke of the embossing member consisting of portions arranged on the actuating element, suitable means attached to the machine for adjusting and guiding the embossing consisting of adjustable set screws for arranging the embossing members in desired relationship with the brick.

55 3. In an embossing machine for a bar of clay, a plurality of rocker arms, an actuating element for moving each arm simultaneously, embossing members attached to the

rocker arms in such a manner that on a movement of the arms the embossing member will contact with the bar of clay in a predetermined manner, means for varying 65 the nature and stroke of the embossing member consisting of portions arranged on the actuating element, suitable means attached to the machine for adjusting and guiding the embossing consisting of adjustable set screws for arranging the embossing members in desired relationship with the bar of clay. 70

4. In an embossing machine for a bar of clay, a plurality of rocker arms, an actuating element for moving each arm simultaneously, embossing members attached to the rocker arms in such a manner that on a movement of the arms the embossing member will contact with the bar of clay in a predetermined manner, means for varying 80 the nature and stroke of the embossing member consisting of portions arranged on the actuating element, suitable means attached to the machine for adjusting and guiding the embossing consisting of adjustable set screws for arranging the embossing members in desired relationship with the bar of clay, and guiding elements for maintaining the embossing member in operative 85 relationship with the bar of clay.

5. In combination with an extrusion machine for making a bar of clay from which brick is cut, a plurality of pivotally arranged rocker arms thereon, embossing member attached to the arms, means connected directly 90 to two of said arms for giving a predetermined movement to all of the rocker arms simultaneously.

6. The combination with a machine having an aperture through which plastic material is extruded in bar form, of a plurality of twisted flexible-cable embossing members extending across said aperture, and means pivotally mounted on the extruding 100 face of said machine to support and reciprocate said members.

7. The combination with a machine having an aperture through which plastic material is extruded in bar form, of a plurality of pairs of rocker arms pivoted on 105 the extruding face of said machine, twisted flexible-cable embossing devices secured to each pair of said arms and extending across said aperture, and means for rocking said arms to reciprocate said devices.

In testimony whereof I affix my signature.
JOHN J. FRED BRAND.
